US0D1096391S

(12) **United States Design Patent** (10) **Patent No.:** **US D1,096,391 S**
(45) **Date of Patent:** **** Oct. 7, 2025**

(54) **ICE CREAM PACKAGE**

(71) Applicant: **Conopco, Inc.**, Englewood Cliffs, NJ
(US)

(72) Inventors: **Kevin Stuart Blake**,
Weston-super-Mare (GB); **James Peter
Dougan**, Bristol (GB); **James Giles**,
Swindon (GB); **Thomas Le Plastrier
Maurice**, Wiltshire (GB); **Ian
Alexander MacKay**, Marlborough
(GB)

(73) Assignee: **Conopco, Inc.**, Englewood Cliffs, NJ
(US)

(**) Term: **15 Years**

(21) Appl. No.: **29/891,488**

(22) Filed: **May 5, 2023**
